UNITED STATES PATENT OFFICE

136,795

DESIGN FOR A LINEAR ACTUATOR FOR MOVABLE PARTS OF AN AIRPLANE OR THE LIKE

William P. Lear, Piqua, Ohio, assigner to Lear
Avia, Inc., Piqua, Ohio, a corporation of Illi-
nois

Application April 1, 1943, Serial No. 109,885

Term of patent 14 years

To all whom it may concern:

Be it known that I, William P. Lear, a citizen of the United States of America, residing at Piqua, in the county of Miami, in the State of Ohio, have invented a new, original, and ornamental Design for a Linear Actuator for Movable Parts of an Airplane or the like, of which the following is a specification, reference being had to the accompanying drawing, forming a part thereof.

In the drawing:

Fig. 1 is a top plan view of a linear actuator for movable parts of an airplane or the like illustrating my new design.

Fig. 2 is a side elevational view of the linear actuator shown in Fig. 1.

Fig. 3 is a left end elevational view of the linear actuator shown in Fig. 1.

Fig. 4 is a perspective view, on a somewhat reduced scale, of the linear actuator shown in Figs. 1, 2 and 3.

I claim:

The ornamental design for a linear actuator for movable parts of an airplane or the like, substantially as shown.

WILLIAM P. LEAR.
